DESIGN FOR A WRIST WATCH STRAP

Joseph E. Du Bois, Snyder, N. Y.

Application March 22, 1945, Serial No. 118,625

Term of patent 14 years

(Cl. D45—4)

To all whom it may concern:

Be it known that I, Joseph E. Du Bois, a citizen of the United States, residing at Snyder, in the county of Erie and State of New York, have invented a new, original, and ornamental Design for a Wrist Watch Strap, of which the following is a specification, reference being had to the accompanying drawing, forming a part thereof.

Figure 1 is a top plan view of the watch strap embodying my new design. Figure 2 is a bottom plan view thereof. Figure 3 is a side view of the same. Figure 4 is an end view of the watch strap.

I claim:

The ornamental design for a wrist watch strap, substantially as shown.

JOSEPH E. DU BOIS.
